UNITED STATES PATENT OFFICE.

EARL HURD, OF NEW YORK, N. Y.

PROCESS OF AND APPARATUS FOR PRODUCING MOVING-PICTURE FILMS.

1,380,298.

Specification of Letters Patent. Patented May 31, 1921.

Application filed October 30, 1919. Serial No. 334,602.

To all whom it may concern:

Be it known that I, EARL HURD, a citizen of the United States, residing at New York, in the county of New York and State of

5 New York, have invented certain new and useful Improvements in Processes of and Apparatus for Producing Moving-Picture Films, of which the following is a specification.

10 In my prior Patent No. 1,143,542 granted June 15, 1915, I have disclosed a method of producing moving picture films especially adapted for animated cartoons. In all prior processes each pose or position of the moving object must be drawn to the proper scale upon a medium preparatory to being photographed. When a series of poses is repeated in producing a complete scene, as in depicting a person or animal walking across 15 the landscape, a set of poses is drawn by the artist showing the successive positions assumed in the act of walking, usually four, six or eight poses being sufficient and then this set of poses is repeated, each pose being 20 advanced in position to give the effect of walking. This repetition of a set of poses may be employed whenever the object is moving across the landscape or screen in the same picture plane. When, however, the 25 object is portrayed as moving toward or from the picture plane it is obvious that each pose will differ progressively in size from the preceding and the succeeding poses in accordance with the laws of perspective. 30 Consequently the different poses of each set differ from each other in size and those of one set differ from the corresponding poses in the preceding and succeeding sets. For this reason it has heretofore been necessary 35 40 for the artist to draw each and every pose throughout an entire action even though it consists of a repetition of identical poses in the several sets because the same object differs in size in each pose throughout the 45 action.

I have devised a method which enables the successive poses to be projected on the pose-carrying medium in any desired size and in any desired position and location from a 50 single set of prepared drawings so that they may be traced by an unskilled person. It is only necessary, therefore, for the artist to prepare one set of poses necessary to form one complete movement, all in the same picture plane, and from this set all of the poses 55 of any number of repetitions of the move-

ment may be projected successively in proper perspective on the pose-carrying media or sheets.

In the following description I shall refer 60 to the accompanying drawings, in which— Figure 1, is a perspective view of a photographic apparatus for preparing the negative containing a series of poses constituting a complete movement or action; Fig. 2 is a 65 transverse sectional view on the line 2—2 of Fig. 1; Fig. 3 is an enlarged vertical sectional view on the line 3—3 of Fig. 2; Fig. 4 is an enlarged detail view of the operating handle for moving the negative carrying 70 frame; Fig. 5 is a perspective view of the apparatus for projecting the poses in the prepared negative upon the pose-carrying media or sheets; Fig. 6 is an enlarged detail view of the lens tube; Fig. 7 is a plan 75 view of a series of transparent sheets or media carrying a series of cartoon poses constituting a complete movement; Fig. 8 is a detail view of a prepared negative and supporting guide; Fig. 9 is a vertical sectional 80 view on the line 9—9 of Fig. 8; Fig. 10 is a plan view of a background showing the stationary parts of a scene with a transparent sheet of celluloid or other suitable material 85 laid thereon and carrying one pose of the movable object or figure; Fig. 11 shows a series of celluloid or other suitable transparent sheets carrying successive poses of a boy as he would appear running across the field of vision; and Fig. 12 is a sectional 90 view on the line 12—12 of Fig. 5.

In carrying out my process it is first necessary for the artist to draw a series of pictures of the moving object showing the different poses which produce a complete 95 movement when projected upon the screen in sequence, each pose being drawn upon a separate sheet and all the same relative size, that is, drawn in the same picture plane. Such a series is shown in Fig. 8, 100 where the four poses of the dog are sufficient, when projected in sequence, to produce the effect of a dog in the act of running, the series being repeated *ad libitum* 105 in continuous succession, pose No. 1 following No. 4.

Having prepared such a series of drawings upon sheets of suitable material of uniform size and each sheet punched with two holes adapted to fit over the supporting 110 and positioning pegs on the exposing easel or support, the negative containing a com-

plete set of poses constituting a movement is prepared with a photographic apparatus such as illustrated in Fig. 1.

As stated above, the sheets 5, upon which 5 the artist has drawn the successive poses of the moving object are placed successively upon the pegs 6 on the easel or support 7. The sensitized medium for producing the negative is preferably carried upon a glass 10 plate 8, and the latter is held in a movable frame 9 within the camera 10. After each exposure the frame 9 is moved a distance equal to the width of one section of the negative, by turning the handle 12 one revolution, thereby causing the pinion 14 to move the rack 15 the required distance to bring the succeeding unexposed section of the plate 8 in alignment with the lens 16. The developed plate provides a negative 20 having a complete series of poses of the moving object, such as that of the dog illustrated in Fig. 8.

For the purpose of producing upon celluloid sheets or other transparent media the 25 poses of the moving object in size or perspective and proper position and location on the sheets to combine with the stationary parts of the setting or background in producing the complete scene as it is to be 30 photographed on the film negative, I employ the apparatus shown in Fig. 5. The projector comprises, as usual, a projecting lamp or lantern, 20 the lens tube 21 carrying a suitable lens and interposed between 35 the lantern and the lens and a guide frame 23, through which the negative 8 may slide, the whole being mounted upon a base block or carriage 25 which may be moved forward or backward along the guide rails 26 of the 40 bench by means of a chain 27 attached to the carriage and engaged by the sprocket 28 on the shaft 29, provided with the handle 30.

At the opposite end of the bench from the projector is a drawing table having the inner side open and an opening in the top corresponding in size to the background. A 45 fixed mirror 37 mounted at an angle of 45° reflects the image of the negative which is projected thereon upwardly upon a sheet of 50 ground glass 38 placed over the opening in the top of the drawing table. The ground glass plate may be moved over the top of the drawing table in the picture plane as desired to adjust the position of the background 55 with respect to the projected object and is provided with two pegs 39 to enter the perforations in the celluloid sheets.

The setting of the scene constituting the 60 stationary background is first sketched on the ground-glass or upon a transparent celluloid sheet which is secured in position over the glass by placing the two punched holes over the pegs 39. A blank celluloid sheet 40 is laid over the background and 65 positioned on the pegs. The first pose of

the moving object is now projected by means of the mirror upon the ground glass and is seen through the transparent celluloid sheet. By shifting the ground-glass over the top of the drawing table the reflection of the 70 moving object is brought into the desired position with relation to the background that is the point at which the "action" starts and by turning the handle 30 in one direction or the other to move the projector 75 nearer or farther away, the size of the moving object is brought to the proper size. The entire scene would then appear like that shown in Fig. 10, except that the black and white colors of the boy would be reversed 80 since it is a negative which is being projected.

After the artist or his copyist has traced the image of the moving object on the celluloid sheet, the negative is slid in the 85 frame 23 a distance which brings the next pose in front of the lens and another celluloid sheet is placed on top of the last sheet. The image projected from the second position or pose on the negative coincides with 90 the figure traced on the first celluloid sheet. The ground glass is therefore shifted laterally until the image of the second pose occupies the position which the moving figure should occupy when it assumes the second 95 pose or position. The reflected image of the moving figure is the same size as the one in the preceding pose and if the moving figure is receding from the picture plane, that is, apparently traveling away from the beholder, the figure of the second pose should be reduced in size. To effect this reduction in size of the reflected image the handle 30 is turned to bring the projector closer to the 100 drawing table, the distance being determined 105 by the desired reduction in size, the lens being adjusted to properly focus the object. The second pose is then traced on the transparent sheet. This proceeding is repeated until the entire series necessary to complete 110 the "action" has been projected and traced upon the successive transparent sheets, the poses on the negative following in sequence and then repeated. In this manner the successive poses of the moving figure or object 115 are made on the successive sheets not only in the proper relative positions but also in the proper size or perspective four sheets of such a series being illustrated in Fig. 7. If a row of these transparent celluloid sheets 120 were superposed the several poses of the moving figure would gradually diminish in size and if these were projected upon a screen in succession they would produce the desired running or other movement. Such 125 a series of sheets is illustrated in Fig. 11.

It will be observed that the entire series of poses continuing *ad libitum*, each diminishing in size in proper perspective was projected from a single negative containing 130

one set of figures required to produce a movement and all the same size, that is, all drawn in the same picture plane. Moreover, as no great amount of skill or artistic ability is required to trace upon the transparent sheets the images reflected upon the ground glass, it is unnecessary to employ a skilled artist for this branch of the work.

After the series of poses on the transparent sheets has been completed, they are placed in sequence over the background and photographed with a moving picture camera to produce a film in the well known manner. Not only has the time and effort of the artist 10 been saved by my process which makes it unnecessary for him to draw each successive pose in the proper perspective, but the graduations of the moving object can be regulated so accurately that a more lifelike 15 and natural motion is produced by my process than has heretofore been attained in cartoon moving pictures.

It is obvious that when it is desired to produce the appearance of the moving figure or object moving toward the observer in which the successive poses of the figure gradually increase in size, it is merely necessary to reverse the operation previously described by successively moving the projector to greater distances from the drawing table and mirror. Likewise if the figure or moving object is to remain in the same picture plane or parallel with the screen throughout successive poses, the projector 35 remains in the same position.

The advantages to be derived from the use of my process will be appreciated by moving picture artists and those familiar with the prior methods of producing cartoon moving picture films. A large part of the laborious work which heretofore required the services of a skilled artist are obviated. The services of an ordinary artisan may be utilized in tracing the figures projected 45 from the negative upon the ground glass. Furthermore the naturalness of the resulting product is enhanced while the speed of production is very greatly increased.

I have described in detail the particular 50 apparatus illustrated in the accompanying drawings but it is evident that I am not restricted thereto in carrying out my process and that many changes may be made therein.

I claim:—

55 1. A process of producing moving pictures which includes forming a series of pictures of a movable object, successive pictures showing the same object in successive positions or poses, photographically producing 60 negatives of said pictures, projecting said negatives in sequence upon transparent sheets to position on the respective sheets the different positions of the object relatively to a background, changing the size of 65 the successively projected negatives to pro-

duce a perspective effect of the movable object, and tracing the images of the projected negatives on the sheets.

2. A process of producing moving pictures which includes forming a series of pictures of a movable object, successive pictures showing the same object in successive positions or poses, photographically producing negatives of said pictures, projecting said negatives in sequence upon transparent sheets to position on the respective sheets the different positions of the object relatively to a background, changing the size of the successively projected negatives to produce a perspective effect of the movable object, tracing the images of the projected negatives on the sheets, superposing said sheets in succession upon a background and photographing the resulting pictures upon a cinematograph film. 85

3. A process of producing moving pictures which includes projecting a series of negatives showing successive poses of a movable object upon a translucent medium, positioning said medium in conjunction with an outlined background with relation to the projected image, adjusting the projected image to the desired size, graduating the sizes of the successively projected images to produce the proper perspective effect of an advancing or receding object, and tracing the images on successive transparent sheets. 95

4. A process of producing moving pictures which includes preparing negatives showing successive poses of the same movable object 100 in the same picture plane, projecting said negatives in succession upon a translucent medium having thereon an outline of a suitable background, moving said medium with the background after the projection of each 105 image to cause a progressive movement of the successive poses relatively to the background, and tracing said successive images upon separate transparent sheets superposed upon said translucent medium. 110

5. A process as defined in claim 4 and wherein the successive projected images are graduated in size to produce the proper perspective effect of an object advancing or receding from the picture plane of the first 115 pose.

6. A process of producing moving pictures which includes preparing negatives of successive poses of a movable object, projecting the images of said negatives through the instrumentality of a reflecting surface upon a transparent medium, positioning said medium in conjunction with the outline of a background to bring said image to a predetermined portion of said background, 120 moving said medium after each projection to cause a relative movement of the successive images thereover and tracing upon separate sheets of transparent material the successively projected images. 125

7. A process as defined in claim 6, wherein the successively projected images of the different poses of the movable object are graduated in size to produce the effect of an advance or recession of said movable object with respect to the picture plane of the first pose.

8. A process of producing moving pictures which includes forming a series of pictures 10 of successive poses of the same movable object upon suitable media, photographically producing a negative having thereon the series of poses, projecting successively 15 the images of said negative upon a translucent medium, graduating the sizes of said images to correspond with an advance or recession of the movable object with respect to the picture plane, and tracing said images

upon separate sheets of transparent material.

9. In combination, a photographic plate or film having thereon the representation of a movable object, a translucent plate or sheet carrying the outline or representation of a scene or background and suitably supported 25 over an opening, means for projecting the image of said object through said opening and upon said plate or sheet, said plate or sheet being movable in the picture plane with respect to the projected image, and a 30 transparent sheet detachably superposed upon said translucent plate upon which said projected image may be traced.

In testimony whereof I affix my signature.

EARL HURD.
